DESIGN FOR A JAR

Fred W. Werts, Muncie, Ind.

Application November 25, 1935, Serial No. 59,746

Term of patent 7 years

To all whom it may concern:

Be it known that I, Fred W. Werts, a citizen of the United States, residing at Muncie, in the county of Delaware and State of Indiana, have invented a new, original, and ornamental Design for a Jar, of which the following is a specification, reference being had to the accompanying drawing, forming a part hereof, and wherein Figure 1 is a front view, and Figure 2 is a top plan view of a jar showing my new design. The sides not shown in Figure 1 are plain.

I claim:

The ornamental design for a jar, as shown and described.

FRED W. WERTS.
